Primary Examiner — Janice Hallmark*Assistant Examiner* — Omeed Agilee(57) **CLAIM**

The ornamental design for an assay plate with sample landing mark, as shown and described.

DESCRIPTION

FIG. 1 shows a top perspective view of an assay plate with sample landing mark.

FIG. 2 shows a bottom perspective view thereof.

FIG. 3 shows a top view thereof.

FIG. 4 shows a bottom view thereof.

FIG. 5 shows a front view thereof.

FIG. 6 shows a rear view thereof.

FIG. 7 shows a right side view thereof; and,

FIG. 8 shows a left side view thereof.
